FIG. 1.

FIG. 2.

FIG. 3.

Inventor
Salem W. Houston
by Herbert W. Jenner
Attorney.

UNITED STATES PATENT OFFICE

SALEM W. HOUSTON, OF PITTSBURGH, PENNSYLVANIA

DOOR HOLDER

Application filed May 18, 1929. Serial No. 364,187.

This invention relates to devices for holding a door in a predetermined position; and it consists of a clamping device specially constructed to hold a door securely in a position to enable the lock seat to be suitably mortised. It is necessary that the door be held securely, and the various wedges ordinarily used for that purpose are not satisfactory as the door is not held with sufficient security, and an injury to the door is often caused thereby.

In the drawings, Fig. 1 is a front view of a door holder constructed according to this invention, showing also portions of the door and floor. Fig. 2 is a plan view of the door holder. Fig. 3 is a detail view of a portion of one of the clamping screws showing the swivelled shoe in section.

A crank-shaped bar 5 is provided having its end portions 6 arranged in line with each other. Screws 7 are arranged to screw in holes 7' in the end portions 6, and are arranged vertically and parallel to each other. Each screw has a shoe 8 at its bottom end, connected to it by a swivel joint 9, and each shoe preferably has a block 10 of india rubber at its bottom. The block is secured to the shoe, and its lower surface is corrugated or roughened in any suitable way. The screws have suitable handles 12, or other means for rotating them, at their upper ends. The bar 5 is made of strong and stiff metal.

The crank-shaped middle portion of the bar is slipped under the bottom portion of the door 14, so that it straddles it, and the screws are screwed down so that the blocks bear hard upon the floor 15. The door is thereby securely clamped in a position so that the mortise for the lock can be cut in it to advantage, and any other work can be done which requires the door to be held securely.

What I claim is:

45 A device for securely clamping a door to a floor, comprising a crank-shaped bar having a middle portion adapted to be slid in the space between the bottom of the door and the floor, vertical portions adapted to project upwardly at the sides of the door,

and horizontal end portions having their lower sides adapted to project above the level of the bottom of the door, clamping screws screwed into the end portions of the bar, and blocks swivelled on the end portions of the screws and provided with facings of relatively soft material for bearing on the floor, said blocks being arranged one on each side of the vertical portions of the bar.

55 In testimony whereof I affix my signature.

SALEM W. HOUSTON.
